UNITED STATES PATENT OFFICE.

LAZARD KAHN, OF HAMILTON, OHIO.

DESIGN FOR A HEATING-STOVE.

SPECIFICATION forming part of Design No. 27,112, dated May 25, 1897.

Application filed April 10, 1897. Serial No. 631,637. Term of patent 14 years.

To all whom it may concern:

Be it known that I, LAZARD KAHN, a citizen of the United States, residing at Hamilton, Butler county, Ohio, have invented and 5 produced a new and original Design for Heating-Stoves, of which the following is a specification, reference being had to the accompanying drawing, showing the same in perspective.

10 The leading feature of my design consists in a body portion in columnar form having a curvilinear outline in plan, the columnar body portion being surmounted by a top ring and having a projecting ring at its base, resting upon legs, the central front of the col-

umnar body portion having a large door of circular outline.

A is the body portion, which is columnar and curvilinear in its plan outline.

B is the projecting top ring, and C is the 20 projecting base-ring, resting on the legs E.

D is the large door in the central front of the columnar body and having a circular outline.

What I claim is—

The design for a heating-stove, substantially as herein shown and described.

LAZARD KAHN.
